US00D441701S

(12) **United States Design Patent**
Okazawa et al.

(10) Patent No.: **US D441,701 S**
(45) Date of Patent: ** May 8, 2001

(54) **OPERATING LEVER FOR WORKING VEHICLE**

D. 414,149 * 9/1999 Asakura D12/179
D. 416,525 * 11/1999 Sacco et al. D12/179
D. 418,097 * 12/1999 Leschke et al. D12/179

(75) Inventors: **Koji Okazawa, Osaka; Akifumi Inamaru; Toshihiro Kawano, both of Oita; Sigeyuki Satou, Saitama, all of (JP)**

* cited by examiner

(73) Assignee: **Komatsu Ltd., Tokyo (JP)**

Primary Examiner—Melody N. Brown

(**) Term: **14 Years**

(74) Attorney, Agent, or Firm—Kanesaka & Takeuchi

(21) Appl. No.: **29/128,976**

CLAIM

(22) Filed: **Sep. 7, 2000**

The ornamental design for an operating lever for working vehicle, as shown and described.

(51) LOC (7) Cl. **12-16**
(52) U.S. Cl. **D12/179**
(58) Field of Search D12/179; D8/303, D8/300; 74/551.8, 551.9, 502.2, 523, 475, 489

DESCRIPTION

(56) **References Cited**

FIG. 1 is a top plan view of an operating lever for working vehicle showing our new design;

FIG. 2 is a front view thereof;

FIG. 3 is a left side view thereof;

FIG. 4 is a right side view thereof;

FIG. 5 is a bottom plan view thereof; and,

FIG. 6 is a rear view thereof.
